UNITED STATES PATENT OFFICE.

ANDREW PALKA, OF DETROIT, MICHIGAN.

DESIGN FOR A RADIATOR.

Application filed January 26, 1926. Serial No. 16,270. Term of patent 3½ years.

To all whom it may concern:

Be it known that I, ANDREW PALKA, a citizen of the United States, residing at Detroit, in the county of Wayne and State of Michigan, have invented a new, original, and ornamental Design for Radiators, of which the following is a specification, reference being had to the accompanying drawing, forming part thereof.

Figure 1 is a front view of a radiator embodying the design.

Figure 2 is a side view of the same.

I claim:

The ornamental design for a radiator, as shown.

ANDREW PALKA.
